PROCESS FOR BLEACHING MOLASSES BY MEANS OF ELECTROLYTIC TREATMENT

Joseph William Thompson and John William Hinchley, London, England

No Drawing. Application April 13, 1931, Serial No. 529,788, and in Great Britain June 2, 1930

2 Claims. (Cl. 204—1)

This invention relates to a process for bleaching molasses by means of electrolytic treatment and the manufacture of yeast therefrom.

Residual liquors from beet and cane sugar manufacture, molasses and more particularly beet sugar molasses, are of a very dark colour and unless they are bleached impart to the yeast produced from them a dark colour also. This is objectionable because the colour of bread made

10 with it is deteriorated. The object of this invention is to overcome this disadvantage and to this end the process consists in diluting the molasses with acidulated water and then subjecting the mixture to the 15 action of an electric current until it is bleached to a predetermined degree. The resultant liquor is then filtered and treated with a reagent to remove impurities and neutralize the acid content. Further features of the invention will 20 transpire in the following description of one embodiment of the process for producing substantially white yeast from beet sugar molasses.

Beet sugar molasses usually contains about 50% of sugars and must be diluted before treatment to reduce the viscosity and increase the 25 surface tension of the solution. A convenient solution is obtained by diluting such molasses to contain about 15% of sugars. A still further dilution may be desirable with very dirty molasses. From $\frac{1}{2}$ to 1 per cent of sulphuric acid 30 is added. This liquor is then allowed to flow through a cell containing electrode plates which may be any material unaffected or only affected slightly by the liquor and the treatment. Graphite or carbon plates are to be preferred. The 35 electrodes are connected to a source of electro-motive force the voltage of which is regulated to pass direct current through the cell at a density of about 1 ampere per square foot.

40 The acid is added to facilitate the process of electrolytic bleaching since the process would normally produce a certain degree of alkalinity. The current is maintained until the mixture is bleached to a degree of approximately 60 per 45 cent and then discontinued. The degree of bleaching may be estimated by means of a tintometer, that is to say, by comparing the color of the bleaching solution with that of a standard solution bleached to a degree of approximately 50 60 per cent. The resultant liquor is then filtered to remove any carbon particles or other 55 impurities suspended therein and finally ammonia, chalk or other suitable re-agent is added to neutralize the acid content. The liquor is then allowed to stand so that any precipitate formed may settle and the solution decanted.

The product of the process described may be further diluted and placed in a brewing tank with the addition of suitable yeast foods such 60 as ammonium phosphate. Mother yeast is added

and air blown through the liquor in the usual manner for the production of yeast.

It is neither desirable, economical nor necessary to completely decolorize the molasses to obtain a white yeast and the process may be stopped at a point where the rate of discharge of colour ceases for a time: usually when about 60 per cent of the colour is discharged. If the bleaching be carried further yeast poisons are produced and the sugars may be seriously attacked.

Any number of carbon plates may be placed in the cell to serve as cathodes and anodes and connected to the source of direct supply accordingly and since they are placed relatively close together they are prevented from short-circuiting by thin strips of non-conducting material 75 suitably disposed.

Although one embodiment of the process has been described by way of example, variations in the proportions of the constituent of the mixture to be treated may be made according to the character or quality of the molasses used. Furthermore, phosphoric or any other suitable acid may be used in lieu of sulphuric acid and similarly 85 any suitable re-agent may be employed to neutralize the acid. All such variations in carrying out the process are intended to be included in this specification and the appended claims.

We claim:—

1. The process of bleaching molasses for subsequent use in the production of yeast, which consists in diluting the molasses until it contains about 15% of sugars, adding one-half to one per cent of a non-poisonous mineral acid, subjecting the mixture to the action of direct electric current until the solution is bleached to a degree of about 60%, filtering the molasses to remove impurities, adding a re-agent to neutralize the acid content of the molasses, and decanting the solution from the precipitate if any.

2. The process of bleaching molasses for subsequent use in the production of yeast, which consists in diluting the molasses until it contains about 15% of sugars, adding $\frac{1}{2}$ to 1% of a non-poisonous mineral acid, passing the solution into an electrolytic cell having carbon electrodes, applying a direct current voltage to said electrodes sufficient to cause a current of approximately 1 ampere per square foot to pass through the solution, maintaining said voltage until the solution is bleached to a degree of approximately 60%, filtering the molasses to remove impurities, adding a re-agent to neutralize the acid content of the molasses, and decanting the solution from the precipitate if any.

JOSEPH WILLIAM THOMPSON.
JOHN WILLIAM HINCHLEY.
